UNITED STATES PATENT OFFICE.

SYDNEY B. LEONARDI, OF TAMPA, FLORIDA.

DESIGN FOR A SPOON.

SPECIFICATION forming part of Design No. 21,348, dated February 16, 1892.

Application filed December 26, 1891. Serial No. 416,267. Term of patent 7 years.

To all whom it may concern:

Be it known that I, SYDNEY B. LEONARDI, a citizen of the United States, residing at Tampa, in the county of Hillsborough and State of Florida, have invented and produced a new and original Design to be Placed and Used on Spoons, of which the following is a specification, reference being had to the accompanying drawing, showing the same.

10 The leading feature of my design consists of an illustration of a columbiad or cannon placed in the ground and represented as firing a projectile to the moon, and which contains a panel upon which may be placed a legend and a name, and is more specifically described as follows: On the inside of the bowl of the spoon is the representation of a cannon or columbiad, the mouth of which shows as if projecting through a plate and from the 15 ground and in the act of firing, such said firing being delineated by the vertical and curved lines in the said bowl of the spoon. Beneath the columbiad or cannon is a panel, upon which

may be placed suitable words, such as "Jules Verne," and in the bowl of said spoon. In 25 the shank or handle of the spoon the vertical lines are continued, and at the top of the shank or handle of the spoon is a representation of the moon, being a circle on which is a representation of a full face. Near and a 30 little beneath the said representation of the moon and on the shank or handle of the spoon is a conical projectile, the point of which is toward the moon. From the top of the bowl of the spoon and running along the shank or 35 handle of the spoon to near the bottom of the said projectile is a panel, upon which may be placed suitable words, such as "Luna Via Tampa, Fla."

What I claim is--

40 The design for a spoon, as herein shown and described.

SYDNEY B. LEONARDI.
